Inventor

Valentine Pajer

By his Attorney Maria Pajer

UNITED STATES PATENT OFFICE.

VALENTINE PAJER, OF BROOKLYN, NEW YORK.

ELECTRIC STEAMER.

Application filed June 3, 1925. Serial No. 34,681.

This invention relates to improvements in electric steaming apparatus in which the heat generated by an electric current, passing through one or more coils of resilient material, is transmitted to water contained in vessel over the coil.

It is one of the objects of the present invention to provide a simple, unitary apparatus, readily portable and easily controlled, whereby a constantly arising vapor may be produced.

It is a further feature to provide means for supporting a hollow perforate receptacle adapted to contain medicaments, perfumes and the like, of a volatile nature, whereby their essential properties are volatilized and caused to rise into the upper part of the apparatus and there utilized.

Another aim is in the provision of a removable cover having an aperture suited to receive the nose or other parts of a person during application of the volatilized material.

These several objects are attained by the novel design, construction and arrangement of parts hereinafter described and shown in the accompanying drawing, constituting an important portion of this disclosure, and in which:

Figure 1 is a vertical sectional view of an embodiment of the apparatus, indicating its operation, the section being taken on line 1-1 of Figure 2.

Figure 2 is a similar view of a modified form thereof.

As shown in the drawing, the apparatus will be seen to consist of a conical base 10 arranged to rest upon any convenient level surface, and having midway in its height a transverse partition wall 11, above which is a chamber 12, in the converging walls, the chamber having an integral cover 13.

Extending out from the side of the chamber 12 is a boss 14, formed to receive insulated conductors 15 and 16 respectively positive and negative, one of which extends between insulators 17 and 18, to a coil 19 encircling a bar 20 below another insulator 21.

The insulator 18 rests on the partition 11 and the insulator 21 is disposed against the cover 13.

It will be understood that the coil 19 is of highly resistant wire, so that when current flows through the conductors 15 and 16, the coil will be heated to a high degree of tem-

perature, this heat just generated filling the chamber and being transmitted to the cover plate 13.

A hollow chamber 22 is formed above the plate 13, having a spheroidal wall 23 adapted to contain liquid as shown, and near the upper edge of the wall is an internal ledge 24.

Normally resting on the ledge is the edge of a fine meshed screen 25, the purpose of which will be later described.

A semi-spherical cover 26 is provided with an annular flange 27 at its lower edge adapted to fit circumjacently the edge of the container wall 23, and in the uppermost central portion of the cover is an opening 28 through which the nostrils may be inserted.

Floating on the liquid contained in the chamber 22 is a hollow container 29, composed of two equal concave convex shells, 75 separably united at their edges and provided with perforations 30 through which emanations from the volatile substances in the container may escape, the container also having a spout 31 directed upward as shown, to terminate below the screen 25.

In the modification shown in Figure 3, the container wall 23 is provided with lugs 32 raised at opposite points from its upper edge and pivoted on these lugs, on pins 34, are 85 two equal curved cover elements adapted to operate smoothly over the surface of the container or form a tight joint at their adjacent edges when closed together, knob handles 36 being provided for convenient handling. 90

In operation, the chamber 22 is provided with liquid to disseminate the heat engendered by the coil 19 when an electric current is turned on, and the container 29 provided with any desired volatile material which 95 is to be used.

Obviously steam rising from the liquid in the chamber 22 will be impregnated and intimately mixed with the vapor from the container 29, and pass together upward through 100 the screen 25, which acts to break up any particles of moisture and unify the vapor passing through.

This vapor is conducted by the cover to the opening 28 where it may be readily inhaled or otherwise applied as desired.

As shown in Figure 3, the cover is in section and the opening therebetween may be increased or diminished at will for the purpose of treating other parts of a person. 110

Having thus described my invention, what I claim as new and desire to secure by Letters Patent, is:—

A steaming apparatus comprising a sectional globular casing having a conical base and a liquid containing chamber directly over said base, means for heating said chamber electrically permanently, fixed in said base, a hollow perforate float in said chamber to contain volatile matter, a screen re-

movably engaged in the lower section of said chamber above the float, and a pair of cover elements hingedly engaging the wall of the chamber and adapted for relative adjustment, to permit application of the vapor rising through said screen, said elements constituting the upper section of the casing.

In witness whereof I have affixed my signature.

VALENTINE PAJER.
